UNITED STATES PATENT OFFICE.

FRANK RASSAT, OF CHICAGO, ILLINOIS.

HYDROCARBON-BURNER.

1,324,468.

Specification of Letters Patent.

Patented Dec. 9, 1919.

Application filed September 25, 1918. Serial No. 255,647.

To all whom it may concern:

Be it known that I, FRANK RASSAT, a citizen of the United States of America, and a resident of Chicago, county of Cook, and 5 State of Illinois, have invented certain new and useful Improvements in Hydrocarbon-Burners, of which the following is a specification.

This invention relates to hydrocarbon 10 burners adapted mainly for use in the fire pots of furnaces, stoves, ranges and such devices, though not necessarily limited to such use.

The main objects of the invention are to 15 provide an improved form of burner for stoves and the like and particularly a compound burner having a plurality of burner arms adapted for adjustment by swinging the arms to different relative positions; to 20 provide for varying the effective heating area of the burner and the intensity of the heat, by turning the direction of one or more of the fuel outlet parts or arms in different directions; and to provide suitable torch and 25 preheating means adapted for use in combination with such swingingly mounted burner arms, in a manner best adapted for convenience in use and efficiency in operation.

An illustrative embodiment of this invention is shown in the accompanying drawings in which:

Figure 1 is a plan of the burner.

Fig. 2 is a side view with one of the burner tubes removed, the view being nearly 30 on the line 2—2 of Fig. 1.

Fig. 3 is a front elevation.

Fig. 4 is a cross section of the burner tubes and connector on the line 4—4 of Fig. 2.

Fig. 5 is an axial section through the gas discharge nozzle and valves.

In the illustrative embodiment shown in the drawings, the burner as a whole comprises a relatively stationary supporting 45 part or frame 1, whereon the other parts are detachably mounted, namely, a fuel supply and vaporizing member 2, a combined air mixing and gas distributing member 3, a pair of tubular gas nozzles or burners 4, each turnably connected medially to said member 3, a torch 5 for starting the burner, and a small vaporizing coil 6 therefor.

Each of the burner members 4 is provided with a central hub part 7 adapted for swinging on the hollow pivot members 8 disposed 50 on the arms 9 of the member 3. The said

pivots are arranged with their axes in the same vertical plane and the said axes are disposed at an angle of about 45 degrees from vertical, hence being at an angle of 60 about 90 degrees from each other.

Each burner part 4 is provided with a series of lateral apertures 10 on one side, the position of said series of apertures or the zone thereof as a whole being about 45 degrees from the axis of the pivot so that when the said burner part is disposed horizontally in one direction the flame will be directed vertically upward, and when the burner part is reversed by swinging said 65 tubular member through an angle of 180 degrees on said pivot the direction of the flame will be horizontal in an outward direction. By virtue of this arrangement the flame may be concentrated by turning both 70 of the burner parts so as to bring the apertures nearest together, that is to say, on the upper side (see Fig. 4) whereby the flames are directed upward side by side. If it is desired to distribute the heat or spread the 75 flames over a wider area, the burner members are reversed so that the flames shoot out sideways in opposite directions and the heat is thereby spread out over a wider area but is less intense at any particular point. The 80 position of the outlet in this position is between the dotted lines 10^a and 10^b on Fig. 4. The burner may be readily changed from one position to the other by reversing the position of the tubular members and the 85 corresponding distribution of heat may be obtained thereby in accordance with the conditions to be met in any particular instance or from time to time as conditions may change.

The said frame 1 comprises a pair of leg members at the front and rear ends respectively, each consisting of a bar formed with its middle part 11 disposed horizontally and with its ends turned down to serve as legs 12, as best shown in Fig. 3. A plate 13 is disposed between the burner tubes 4 and is attached adjacent to its ends to the said parts 11 of the leg members by suitable means as screws 14. The front end 14' of plate 14 is turned up as shown in Fig. 2. The ends 14'' bear against the tubes 4 and coöperate with the outwardly turned knees 12' of the legs 12 to grip said tubes. There is also provided at each end of the frame 100 an upwardly disposed bracket or clamp member 15 also held in place medially by

the corresponding screws 14. The ends 16 of said brackets 15 are turned upward and inward to clasp the parallelly disposed arms of the U-shaped vaporizing member 2, the 5 latter being slidably lengthwise therein when the connector 17 is released, as hereinafter described. On the front end of the plate 12 is attached a sheet of asbestos adapted to receive a suitable charge of oil from the pipe 10 6, and so constitute the torch 5.

The said pipe 6 is formed with a long tubular connection extending from the connector 17 upward through an aperture 18 in the middle part of plate 13 and a spirally 15 coiled part terminating at the front end in a rearwardly facing nozzle 19 adapted to throw a stream of oil backward onto the asbestos and into the coil, this being shown in Fig. 1. The tip 20 of the tube 6 is sealed 20 and the said nozzle for the escape of fuel is disposed on the inner side of the rearwardly turned end part of the pipe.

The mixing chamber 3 comprises a forwardly extending part 21 which is cut away 25 and left open at the lower front corner, as shown at 22. The closed upper part fits over the gas nozzle 23, and air is admitted through the opening 22 so that air and gas will be carried forward together and mixed 30 as it approaches the upwardly turned arms 9 which lead to the corresponding burner tubes 5.

Fuel is supplied to the vaporizing chamber through the valve mechanism 24 on the front 35 end of the right hand arm of the vaporizer as viewed in Fig. 1. The lower valve member 25 supplies liquid fuel to the torch through the pipe 6 and the upper valve supplies fuel to the vaporizing chamber. On 40 the front end of the opposite or left arm is provided a valve attachment 26 including a pair of valve members. The upper valve 27 controls the flow of the fuel vapor through the gas nozzle 23 into the mixing 45 chamber, and the lower valve 28 controls the waste blow-off nozzle 29 and is normally closed.

The operation for reversing the position of the burner tubes is as follows: First disconnect the priming torch coil 6 by unfastening the connector 17, then withdraw the vaporizing member 2 by relative forward movement thereof with respect to the frame 1, then remove the frame screws 14 so as to 55 permit the leg members 11—12 to separate

from the frame plate 13 and both are removed from the burner tubes, which then remain connected solely by the angular gas supply member 3—9. The burner tubes are then free to be turned on their respective 60 pivots and may be reversed one after the other.

The operation for assembling the device is as follows: The combined fuel mixing and distributing chamber and burner tubes being in their normal position with the burner apertures facing either upward or outward, the frame plate and leg members are assembled in place and secured by the screws 14. The vaporizing tube 2 is then inserted by longitudinal movement lengthwise of the burner tubes in a backward direction from the front end of the device. The priming spiral is then inserted and secured in place by setting the connector clamp 75 17 in place, whereupon the device is ready for use.

Although but one specific embodiment of this invention has been herein shown and described, it will be understood that numerous details of the construction shown may be altered or omitted without departing from the spirit of this invention as defined by the following claims.

I claim:

1. A hydrocarbon burner, comprising a relatively stationary support having a pair of hollow pivots disposed with their axes at an angle of about 90 degrees, in combination with a pair of tubular burner members 90 swingingly mounted on said pivots respectively, the pivotal attachment of said members being central on one side thereof respectively, and the fuel apertures of each of said members being disposed in a longitudinal zone about 45 degrees from the corresponding pivotal axis.

2. A hydrocarbon burner, comprising a vaporizing tube having a combined discharge valve and nozzle device at one end, 100 and a fuel supply valve device at the other end, the former of said devices including a gas discharge nozzle and waste collecting means thereunder, said collecting means having a valve adapted for manual control to 105 release the waste material from time to time.

Signed at Chicago this 23rd day of Sept., 1918.

FRANK RASSAT.
